UNITED STATES PATENT OFFICE.

CARL GUSTAV PFINGSTEN, OF NEW YORK, N. Y.

DESIGN FOR A BELT-BODY.

SPECIFICATION forming part of Design No. 32,767, dated May 29, 1900.

Application filed April 12, 1900. Serial No. 12,643. Term of patent 3½ years.

To all whom it may concern:

Be it known that I, CARL GUSTAV PFINGSTEN, a citizen of the United States, and a resident of New York city, county and State of New York, have invented a new and original Design for a Belt-Body, of which the following is a specification, reference being had to the accompanying drawings, in which—

Figure 1 is a view of a belt-body, showing the design; and Fig. 2, a longitudinal section of the same on line 2 2, Fig. 1.

The leading feature of the design consists of a belt-body having a pair of serpentine rear sections *a b*, that cross each other and merge

into two straight front sections *c*. These straight front sections are narrower than the serpentine rear section, so that the windings of the latter project above and below the former.

What I claim is—

The design for a belt-body, substantially as herein shown and described.

Signed by me at New York city, county and State of New York, this 11th day of April, 1900.

CARL GUSTAV PFINGSTEN.
